J. M. LUCARELLE

EJECTOR

Filed Oct. 27, 1923

FIG. 2

UNITED STATES PATENT OFFICE.

JOSEPH M. LUCARELLE, OF BRIDGEPORT, CONNECTICUT, ASSIGNOR TO DICTAPHONE CORPORATION, OF BRIDGEPORT, CONNECTICUT, A CORPORATION OF NEW YORK.

EJECTOR.

Application filed October 27, 1923. Serial No. 671,192.

This invention relates to phonographs and other recording machines, and more particularly to dictating and transcribing and allied machines.

5 An object of this invention is to provide an improved record-ejector for freeing the record from its supporting means.

Another object is to provide a record-ejector with which the operator may, with one 10 hand, simultaneously free the record from its supporting means and grasp the free end preparatory to removing the record therefrom.

A further object is to provide a record-ejector having the parts so arranged that the operator's thumb may actuate the ejector while the index and middle fingers are in line with the end of the record to engage its inside surface when ejected.

20 A still further object is to provide a record-ejector having its actuating part so positioned that it does not interfere with the operation of any of the parts of the machine or with the record.

25 And yet another object is to provide a record-ejector with which very little effort is required to free the record from its support, which, in the embodiment shown, is a mandrel of the self-adjusting type having 30 spring pressed devices to yieldingly engage and hold the record.

Other features and advantages will hereinafter appear.

In the accompanying drawing:

35 Figure 1 is a perspective view of a dictating machine of the "dictaphone" type showing the operator's hand in the act of ejecting the record and removing it from the mandrel.

40 Fig. 2 is a plan view of the bottom of the machine frame showing the operating parts of the ejector.

Fig. 3 is a front elevation of the machine showing the ejector in operating position.

45 The dictating machine shown in the accompanying drawing has a base 10, with vertical standards 11 provided with suitable guides 12, upon which there is slidably mounted a sound-box carriage 13. The

50 sound-box carriage is connected with a speaking tube 14 which is supported when out of use upon a hook 15 at the left-side of the machine. At this side of the machine there

is also provided a housing 16 having bearings for the shaft 17 of the mandrel 18 which 55 supports the wax-like cylinder or record upon which the recording of the sound is done.

The mandrel 18 is tapered to fit the tapered inside surface of the record, and is 60 provided with a plurality of spring pressed plungers 19 which frictionally engage the inside surface of the record to securely hold the record on the mandrel.

When the record is being applied to the 65 machine, it is placed upon the mandrel, and then gently pushed, by the operator's fingers engaging its end, until the other end of the record engages a flange 20 on the mandrel.

Heretofore, the ejector device provided for 70 freeing the cylinder from the mandrel was mounted on the housing 16 directly beneath the hook 15 for the speaking-tube. This structure, while being itself satisfactory in 75 operation, nevertheless, was inconvenient to operate because the speaking-tube hanging upon the hook 15 was in the way; and it was necessary for the operator to remove the speaking-tube from the hook during the 80 operation of the ejector. Further, with this form of ejector, it was necessary for the operator to operate the ejecting-lever with one hand while holding the fingers of the other hand in line with the mandrel to receive the record when it was ejected. It is the object 85 of this invention to avoid these difficulties and the following is a description of one exemplary embodiment of this invention.

For ejecting the record there is provided 90 a plunger 21 supported in the bearing member or housing 16 to move longitudinally of the machine. The operating end of the plunger 21 has a head 22 so shaped as to pass by the flange 20 but to engage the end 95 of the record when the plunger 21 is reciprocated. The other end of the plunger 21 is provided with a hooked portion 23 adapted to engage the notched end 24 of an upstanding arm 25 forming part of a longitudinally disposed link 26. This link 26 extends below the base 10 of the frame and terminates at a point approximately in line with the end of the mandrel. At this end, the link 26 is connected to a lever 27 by a shouldered screw 28. The lever 27 is fulcrumed upon a stud 29 at the rear of the machine, and at its for- 100 105

ward end it is provided with an upwardly extending portion 30 forming a finger-piece by means of which the lever may be operated. This finger-piece extends through a slotted plate 31 covering a suitable opening 32 left in the casting forming the base 10. The ends of the slot in the plate 31 serve as stops for limiting the movement of the lever 27.

The parts are held in their normal positions by means of a spring 34 having one end connected to the link 26 and the other end connected to the lever 27 adjacent the point of connection of the link and lever. The tendency is for the spring 34 to pull the lever 27 to the left as seen in Fig. 2, and since, when the lever moves to the left, the plunger and the links 26 must also move to the left, the spring maintains the entire device in inoperative position. It should be noted that the spring is not attached to any part of the frame-work but merely to the lever system of the ejector and therefore the device may be installed without attaching any parts to the framework other than the stud 29 for the lever 27.

If desired the link 26 may be guided in its movement by a shouldered screw 35 passing through a slot 36 in the link. This will hold the lever 27 connected with the link against undesirable downward movement.

The finger-piece 30 is arranged so as to project above the base 10 in close proximity to the end of the mandrel 18. This enables the removal of the record by the operator's thumb engaging the finger-piece 30, as shown in Fig. 1, while the index finger and middle finger are in engagement with the mandrel. When the ejector lever is operated, with the hand in this position, the record is pushed from the mandrel against the holding force of the spring-pressed plungers 19 onto the ends of the operator's fingers. The operator then grasps the record by its inside surface using these two fingers and lifts the record from the machine. It should be noted that this operation is done with only one hand and that the speaking-tube may be supported upon the hook 15 at the time of record ejecting, leaving the operator's other hand free for other purposes, such as reaching for the carton in which the record is to be put.

Attention is called to another advantage of the kind of construction above described over that previously in use. Heretofore, it has been necessary, in some cases where the record has shrunk, or contracted, or where the spring-pressed plungers 19 are extraordinarily stiff, for the operator to hold the machine, which it should be remembered is usually mounted upon casters, during the operation of the ejector for there was a tendency for the entire machine to roll along the floor. Now, with the operator's fingers engaging the mandrel itself, while the thumb is engaging the record-ejector, there is no

such tendency, for the force applied against the record-ejector reacts through the operator's fingers upon the mandrel. In other words, the mandrel is a fulcrum point of the operator's hand in moving the ejector.

While the finger-piece 30 is located at the discharge end of the mandrel, it is, however, located so far forwardly with respect thereto that there is no danger of the record coming in contact with the finger-piece when it is being placed upon the mandrel.

Since the operator's fingers are in position to receive the record when it is ejected it is now possible to impart a greater movement to the record than has heretofore been advisable, for it was frequently the case that the operator in ejecting would so forcibly operate the ejector that the cylinder would be thrown off the mandrel onto the floor, and being fragile would, of course, break, causing in some cases an irreparable loss.

While there is here shown and described a specific embodiment of this invention it should be understood that there are many other ways of carrying out the inventive idea involved and that this invention is not limited to the specific construction shown.

Having now described the invention, what is claimed as new and for which Letters Patent of the United States is desired, is:

1. In combination, a frame, a record-support mounted thereon, an ejector-head for engaging a record held on the support and adapted to move the record longitudinally of the support, and means mounted on the frame for operating the ejector-head including a finger-piece movable in a horizontal plane parallel to the horizontal plane in which the record moves when ejected, located adjacent the discharge end of the record-support and in a plane cutting the record between its ends so that an operator's finger may receive the record from the record-support while part of the same hand operates the finger-piece.

2. In combination, a frame, a record-support mounted thereon, an ejector-head for engaging a record held on the support and adapted to move the record longitudinally of the support, and means mounted on the frame for operating the ejector-head including a thumb-piece positioned adjacent the discharge end of the record-support and movable toward the discharge end of the record-support so that an operator's finger may receive the record from the record-support while the thumb of the same hand operates the thumb-piece of the ejector.

3. In combination, a frame, a record-mandrel mounted on the frame, and record-ejecting means for freeing the record from the mandrel and including a manually operative part located adjacent the discharge end of the mandrel and in proximity to the end of the mandrel which may act as a purchase.

for the hand of the operator while engaging and operating said manually operable part.

4. In combination, a frame, a record-support mounted on the frame comprising a mandrel carrying spring-pressed plungers for frictionally holding the record thereon, an ejector-head for engaging the record and moving it longitudinally against the pressure of the plungers to free the record therefrom, means for operating the ejector-head including a power increasing leverage system and a manually operable part located in the frame adjacent the discharge end of the mandrel, and means for automatically returning said ejector-head to inoperative position when said manually operable part is released to permit replacement of a record without interference from the said ejector-head.

5. In combination, a frame, a record-mandrel mounted on the frame, a longitudinally movable plunger for engaging a record supported by the mandrel for freeing the record therefrom, a longitudinally disposed link connected to the plunger, a lever mounted on the frame and connected to the link, and a manually operable part connected to the lever and located adjacent the discharge end of the mandrel, said lever being so remote from said record-mandrel as to permit removal or replacement of a record without interference with the lever.

6. In combination, a frame, a record-mandrel mounted on the frame, record-engaging means for ejecting the record from the mandrel, a link connected to the record-engaging means, a lever connected to the link, and a finger-piece on the lever and located adjacent the discharge end of the mandrel, said lever being so remote from said record-mandrel as to permit removal or replacement of a record without interference with the lever.

7. In combination, a frame, a record-mandrel mounted on the frame, a longitudinally movable, record-engaging plunger mounted on the frame and having a notch at its end, a longitudinally disposed link mounted beneath the frame, and having an upstanding arm provided with a part to engage the notch in the plunger, a lever pivoted to the underside of the frame, means interconnecting the lever and link, and a finger-piece on the lever extending upwardly

through an opening in the frame for manual operation.

8. In combination, a frame, a record-mandrel mounted on the frame, a longitudinally movable, record-engaging plunger mounted on the frame and having a notch at its end, a longitudinally disposed link mounted beneath the frame and having an upstanding arm provided with a part to engage the notch in the plunger, a lever pivoted to the underside of the frame, means interconnecting the lever and link, and a spring between the link and lever adapted to return the parts to normal position after operation.

9. In combination, a frame, a record-mandrel mounted on the frame, a longitudinally movable, record-engaging plunger mounted on the frame and having a notch at its end, a longitudinally disposed link mounted beneath the frame and having an upstanding arm provided with a part to engage the notch in the plunger, a lever pivoted to the underside of the frame, means interconnecting the lever and link, and a single spring adapted to hold all of the parts in inoperative position.

10. In combination, a frame, a record-mandrel mounted on the frame, a longitudinally movable record-engaging plunger mounted on the frame, a longitudinally disposed link mounted beneath the frame and engaging the record-engaging plunger, a lever pivoted to the underside of the frame, means interconnecting the lever and link, and a finger piece extending through an opening in the frame for manual operation.

11. In combination, a frame, a record-mandrel mounted on the frame; a longitudinally movable record-engaging plunger mounted on the frame; a longitudinally disposed link mounted beneath the frame and engaging the record-engaging plunger; a lever pivoted to the underside of the frame; means interconnecting the lever and link; manually operable means on the lever extending through an opening in the frame to accessible position for manual operation; and means mounted on the frame for guiding the longitudinally disposed link in its longitudinal movement.

Signed at Bridgeport, in the county of Fairfield, and State of Connecticut, this 24th day of October, 1923.

JOSEPH M. LUCARELLE.
